UNITED STATES PATENT OFFICE.

JOHN K. CLARK, OF BUFFALO, NEW YORK.

RAIL SUPPORT OR TIE FOR RAILWAYS.

SPECIFICATION forming part of Letters Patent No. 323,275, dated July 28, 1885.

Application filed August 18, 1884. (No model.)

To all whom it may concern:

Be it known that I, JOHN K. CLARK, a citizen of the United States, residing at Buffalo, Erie county, New York, have invented new 5 and useful Improvements in Rail Supports or Ties for Railways, of which the following is a specification.

This invention has for its objects to provide an efficient support for the rails of railroads; 10 to avoid the use of wooden ties; to provide novel means for connecting metallic rail-supports, whereby I provide a solid bearing and a base for the ballast; to provide a novel tie-plate and means for connecting two opposite 15 metallic rail-supports; to provide a continuous or unbroken bearing of the rail-supports and the connecting tie-plate on the road-bed, and to provide such construction and union of parts that a practically solid structure is 20 secured adapted to rest squarely and evenly on the road-bed and be properly confined in position by the ballast.

The objects of my invention are accomplished by the construction and combination 25 of devices hereinafter described and claimed, reference being made to the accompanying drawings, in which—

Figure 1 is a perspective view of two of the rail-supports and connecting tie-plate, comprising the completed tie; Fig. 2, a longitudinal central sectional view taken vertically through the supports and tie-plate; Fig. 3, a detached perspective view of one of the rail-supports; Fig. 4, a detached perspective view 35 of the tie-plate; and Fig. 5, a vertical sectional view of one of the rail-supports, showing a modification of the invention.

The present invention is of the general character shown and described in my application 40 for Letters Patent filed January 22, 1884, Serial No. 120,730, and I do not therefore wish to be understood as broadly claiming what is embraced in the said application.

In order to enable those skilled in the art 45 to make and use my present invention, I will now describe the same in detail, reference being made to the drawings, where it will be seen that each of the rail-supports is composed of a horizontal bottom wall or 50 base number, 1, vertical side walls, 2, a transverse top plate, 3, to which the rail is secured, and a central vertical web, 4, joined

to the top plate and the bottom and side walls, the side walls being inclined from the end of the top plate to the ends of the bottom plate, whereby I provide a narrow top bearing-surface for the rail as compared to the extended base which rests on the road-bed. The bottom plate is formed with a rectangular slot or perforation, 5, adjacent to the web 4, and 55 the under side of the said wall is formed with a rectilinear recess extending from the web to the end of the wall to constitute a depressed seat, 6, for receiving one end of the tie-plate 7, so that when the latter is in the seat its 65 lower surface may be flush with the lower surface of the support. The tie-plate is rectilinear in shape, and at each end is provided with a standard, 8, formed as a flange, having a perforation, 9, adjacent to its upper extremity 70 such standards passing through the perforations 5 in the bottom walls and engaging bolts 10, secured to the webs of the supports. These bolts are provided with heads and pass through the webs, to which they are attached at their 75 inner end portions by screw-nuts 11, leaving the projecting threaded portion of the bolt to pass through the standards of the tie-plates and engage screw-nuts 12, which screw up against the standards to clamp them against the nuts 11. The tie-plates are ribbed longitudinally along their margins, as at 13, to provide strength, and are formed with two orifices, 14, and raised lips 15, which project in opposite directions and respectively overlap 85 the recessed ends of the bottom walls of the supports to hold such ends down and secure a strong and substantial connection of the parts. The object of the orifices is to permit the lips 15 to be formed by punching or molding up 90 the metal, thereby forming the lips and creating the orifices.

The ends of the tie-plate, being seated in depressed seats in the bottom walls of the supports, prevent any lateral movement of the 95 support in relation to the tie-plate, as well as bring the parts flush to preserve the continuity of the bearing of the structure on the road-bed, and also obtain a broad or extended and continuous bearing on the road-bed intermediate the supports, the whole constituting, as it were, a solid structure or tie from end to end. The ballast—such as broken stones, &c.—is packed into the supports and upon the tie-

plate, and as the latter rests on the road-bed in line with the bases of the supports, a firm and substantial railway-tie is produced.

The manner of connecting the rails with the top plate may be through the medium of the diagonally - arranged overhanging lugs 17, forming part of the top plate, as in my application before alluded to, and as shown in Figs. 1 and 2 of the drawings; or I may connect the rails with the top plates by hooked screw-bolts, as shown in Fig. 5. In this example the top plate will be provided with square or angular orifices, through which pass the square shanks of the hooks 18, the hooks engaging the flanges of the rails, and the shanks of the hooks having screw-threaded extremities engaging screw-nuts 19 under the top plates of the supports, so that by screwing up the nuts the hooks clamp the rail-flanges on the top plate, while the angular form of the hook-shanks and angular sockets in the top plate prevent the hooks from turning in any direction. The orifices for the bolts 10 and for the hooks 18 will be cored out during the process of casting the rail-supports to avoid the expense of drilling, and the rail-supports and tie-plates are preferably composed of malleable iron; but I do not confine myself to any special means of forming the orifices or to any particular metal in the construction of the invention. The depressed seats in the bottom walls of the rail-supports are formed by raising the metal of the walls, as at 20, thus imparting a bridged or angular form to the walls, so that they are of uniform thickness and considerably strengthened.

Having thus described my invention, what I claim is—

1. A rail-support consisting of the top plate, the side walls, the web, and the bottom wall having a rectilinear depressed seat in its under side to receive the end of a rectilinear tie-plate, substantially as described.
2. A rail-support consisting of the top plate, the side walls, the web, and the bottom wall having the slot or perforation and the rectilinear depressed seat for receiving the end of the rectilinear tie-plate, substantially as described.
3. The combination of the two rail-supports, each composed of the top plate, the side walls, the web, and the horizontal bottom wall hav-

ing a rectilinear depressed seat with the rectilinear tie-plate having its end portions confined in the depressed seats, substantially as described.

4. The combination of the two rail-supports, each composed of the top plate, the side walls, the web, and the horizontal bottom wall having the depressed rectilinear seat, with the tie-plate arranged in said seats, and having standards connected with the web, substantially as described.

5. The combination of the two rail-supports, each composed of the top plate, the side walls, the web, and the horizontal bottom wall having the slot or perforation and the rectilinear depressed seat in its under side, with the tie-plate arranged in said seats, and having standards at its extremities and bolts connecting the standards to the web, substantially as described.

6. The combination of two rail-supports, each having a top plate to receive the rail, and an extended bottom wall having a rectilinear seat, with a tie-plate secured in said seats, with its lower surface flush or substantially flush with the lower surfaces of the said bottom walls, substantially as described.

7. The combination of the two rail-supports, each composed of the top plate, the side walls, the vertical web, and the horizontal bottom wall, with a rectilinear tie-plate connecting the adjacent ends of the bottom walls of the supports and arranged in the plane of the said bottom walls, substantially as described.

8. The combination of the two rail-supports having the webs, the tie-plates having the end standards, the bolts and nuts connecting the end standards with the web, and means for securing rails on the top plate, substantially as described.

9. The tie-plate having the oppositely-projecting raised lips and end standards, in combination with the rail-supports having webs to which the standards are attached and bottom walls engaging the lips, substantially as described.

In testimony whereof I have affixed my signature in presence of two witnesses.

JOHN K. CLARK.
